(57) CLAIM

The ornamental design for an egghead sports fanatic hat, as shown and described herein.

DESCRIPTION

FIG. 1 is a front elevational view of the egghead sports fanatic hat.

FIG. 2 is a left side elevational view of the egghead sports fanatic hat of FIG. 1.

FIG. 3 is a back elevational view of the egghead sports fanatic hat of FIG. 1; and,

FIG. 4 is a top plan view of the egghead sports fanatic hat of FIG. 1.

The broken lines showing of the human head in FIGS. 1 through 3 are for illustrative purposes only and form no part of the claimed design.
